CLAIM

(57) What is claimed is the ornamental design for an outdoor grill, as shown and described.

DESCRIPTION

FIG. 1 is a top, front, and left side isometric view of the outdoor grill showing our new design.

FIG. 2 is a front elevational view thereof

FIG. 3 is a left side elevational view thereof

FIG. 4 is a rear elevational view thereof;

FIG. 5 is a right side elevational view thereof; and,

FIG. 6 is a top plan view thereof.

The details show in broken lines form no part of the claimed design.
